UNITED STATES PATENT OFFICE

EDWARD L. USNER, OF PHILADELPHIA, PENNSYLVANIA

DIMMER FOR VEHICLE HEADLIGHTS

Application filed August 23, 1933. Serial No. 658,793.

My invention provides improved means for positively controlling the current furnished the head lights of vehicles, so as to either "dim" such headlights or maintain their full brilliancy by a simple manual operation. Such control is most conveniently effected by means of the foot or knee, and hence it is important that the movement required be a simple pressure for changing the lights from "bright" to "dim" and vice versa, and that the lights continue in either the "dim" or in the "bright" condition without attention from the operator until the mechanism is again actuated. By the mechanism embodying my improvements the control of the lights is effected by pressure of a single member always in the same direction, so that the changes in the light conditions may be made by the operator without any uncertainty as to what part should be operated or how it should be operated.

In the preferred embodiment of my invention, there are provided conductors forming a path for current flowing to the lamps to light them to full brilliancy, and a secondary path containing resistance permitting flow of a reduced amount of current to provide "dim" lights when the main path is interrupted by the shifting of a switch blade. The switch blade is moved to "make" and "break" positions alternately by successive movements in one direction of a manually operable member to close or open the main current path.

In the accompanying drawings, Fig. 1 is a diagrammatic view of a lighting layout embodying my invention; Fig. 2 is a vertical sectional view of a preferred embodiment of the novel portion of the apparatus; and Fig. 3 is a sectional view on the line 3-3 of Fig. 2.

As illustrated in the drawings, the battery A has one of its terminals connected through a dash board control switch B to the conductor 30 for supplying current to the headlights C through the mechanism hereinafter described and the conductor 1. The circuit between the battery and headlights may be completed by grounding them upon the vehicle frame or by means of a suitable conductor. A switch box 8, fixed to a panel 10, contains a spring supported bus bar or electrode 25 to

which the conductor 30 is connected by a terminal screw 24. A contact bar or electrode 23, insulated from the bar 25, has connected therewith, by a terminal screw 21, a conductor 9 forming an extension of the conductor 1. A contact bar or electrode 19 is supported on the panel 22 and extends around one end of the electrode 23, from which it is insulated. The bar 19 has connected therewith, by a terminal screw 20, a conductor 7 connected with the terminal 6 of a resistance coil 5 disposed in a box 4 depending from the panel 10, the opposite end of the resistance coil being connected, through the terminal 3 and conductor 2, with the conductor 1.

A shaft 29, fixed to the panel 22, has sleeved a switch blade 27 connected through the spring 31 with a ratchet wheel 26 and constantly contacting with the corrugated electrode 25 and contacting alternately with the electrodes 19 and 23. The switch blade is rotated through the spring, step by step, by means of the ratchet wheel 26 journaled on the shaft, and a pawl 28 pivoted on the stem 14, the pawl being supported by a leaf spring 18 and its upward movement being limited by a stop 32.

The stem 14 is reciprocable through end apertures in the bushing or thimble 17 and has a pin 12 fixed therein and engaged in slots formed in the side walls of the thimble to limit the movement of the stem. A coiled spring 16, disposed between the end of the thimble and the pin 12, normally retracts the stem 14 and elevates the pawl 28. A dust guard and support 11 is screwed on the thimble 17 and engages the surface of the panel. The stem 14 has fixed thereto a collar 15 and a button 13 for actuating it.

With the parts in the position shown, when the dash switch is closed, current flows from the battery through the dash switch, conductor 30, electrode 25, switch blade 27, electrode 19, conductor 7, resistance coil 5, conductors 2 and 1 to the lamps, supplying a reduced amount of current for providing dim light. Current will continue flowing through this path until the vehicle operator presses on the button 13 to depress the stem 14 and cause the pawl 28 to move the blade 27 one-

eighth of a revolution, whereby the blade is disengaged from the electrode 19 and contacts with the electrode 23. Current then flows from the battery, dash switch, conductor 30, electrode 25, switch blade 27, electrode 23, and conductors 9 and 1 to the headlights, lighting them to full brilliancy. This condition is maintained until the button 13 is again depressed to move the switch blade 27 through a partial revolution which moves the blade segment previously engaging the electrode 25 into engagement with the electrode 19 and moves the blade segment previously engaging the electrode 23 into contact with the electrode 25 to again dim the lights.

Having described my invention, I claim:

1. A headlight control mechanism comprising the combination of an electrode adapted for connection with a source of electricity, a contact member adapted for connection with the headlight, a second contact member adapted for connection with said headlight, one of said contact members providing contact surfaces on opposite sides of the other contact member, and a switch blade connected with said electrode and movable into engagement with said contact members alternately.

2. A headlight control mechanism comprising an electrode adapted for connection with a source of electricity, a plurality of contacts adapted for connection with a headlight, switching mechanism comprising a manually reciprocal plunger and a journalled member provided with a blade having its opposite ends movable into or out of engagement with said electrode and with said contacts in alternation upon manual movement of said plunger in one direction only.

3. A headlight control mechanism comprising an electrode adapted for connection with a source of electricity, a contact, switching mechanism comprising a manually reciprocal member, a spring, and a blade rotatable through said spring by movement of said member in one direction only, successive manual operation of said member alternately engaging said blade with and disengaging it from said contact, and a second contact insulated from the contact first named and engaged by said blade when disengaged from said contact first named.

4. A device of the character described comprising a reciprocal plunger, a spring moving said plunger in one direction, a conducting blade rotatable in one direction only by the movement of said plunger against the action of said spring, an electrode connected with said blade, and a plurality of contacts insulated from each other and alternately connected by said blade with said electrode, said blade contacting with both contacts simultaneously during movement of said blade from one contact to the other.

5. A headlight control mechanism com-

prising a rotatable switch blade, an electrode curved about the axis of rotation of said switch blade and adapted to be engaged by the opposite ends thereof, a curved contact on the opposite side of the axis of said switch from said electrode, and a curved contact lying between the axis of said switch and said contact first named.

6. A headlight control mechanism comprising a rotatable switch blade, an electrode lying on one side of the axis of rotation of said switch blade and engaged by contact surfaces at the opposite ends of said switch blade, and a plurality of contacts on the opposite side of said axis from said electrode and engaged by the surfaces of said switch blade which engage said electrode.

In testimony whereof I have hereunto set my name this 30th day of July, 1923.
